(57) **CLAIM**

The ornamental design for an electronic vaping device, as shown and described.

DESCRIPTION

FIG. 1 is an upper front perspective view of an electronic vaping device;

FIG. 2 is a lower, rear perspective view of the electronic vaping device of FIG. 1;

FIG. 3 is a lower, front perspective view of the electronic vaping device of FIG. 1;

FIG. 4 is a front elevation view of the electronic vaping device of FIG. 1;

FIG. 5 is a rear elevation view of the electronic vaping device of FIG. 1;

FIG. 6 is a right side elevation view of the electronic vaping device of FIG. 1;

FIG. 7 is a left side elevation view of the electronic vaping device of FIG. 1;

FIG. 8 is a top plan view of the electronic vaping device of FIG. 1; and,

FIG. 9 is a bottom plan view of the electronic vaping device of FIG. 1.

The broken lines in the drawings depict portions of the electronic vaping device that form no part of the claimed design.

1 Claim, 6 Drawing Sheets
